HEEL SEAT FITTING MACHINE

John T. Lancaster, Newton, Mass., assignor to
 United Shoe Machinery Corporation, Flemington, N. J., a corporation of New Jersey

Application September 12, 1945, Serial No. 615,829

20 Claims. (Cl. 12—31.5)

1

This invention relates to shoe machinery and is illustrated as embodied in a heel seat fitting machine.

Various types of machines have been proposed for preparing the heel-seat portions of attached outsoles of shoes for the reception of heels. In most of said types of machines the heel ends of shoes of different sizes are located in different positions to be operated upon in the machines, with relation to trimming instrumentalities, by 10 rather complicated and expensive gaging mechanism.

It is an object of the present invention to provide a machine in which the rear ends of shoes of different sizes are located in the same position in the machine and which has trimming instrumentalities which may be moved into different operative positions so as properly to fit the attached outsoles of shoes of different sizes thus positioned for the reception of heels.

With the above object in view and in accordance with a feature of the present invention, there are provided, in combination with a fixed back gage and crease plates constructed and arranged to enter the rand crease of a shoe, means comprising cutters or knives constructed and arranged to form heel breast receiving shoulders on the outsole of the shoe and initially adjustable into different operative positions lengthwise of the shoe, a heel seat reducing or tab forming cutter or knife mounted for trimming movement lengthwise of the shoe, and means for varying the amount of trimming movement of said heel seat reducing cutter in accordance with the setting of said shoulder forming means lengthwise of the shoe.

Before presenting the shoe to the machine, the heel breast line of the attached outsole of the shoe is established, after properly positioning upon the heel-seat portion of said outsole a heel to be attached to the shoe, by drawing a line across the outsole along the forward edge of the lip of the positioned heel. The shoe is presented to the machine, heel end first and bottom up, by the operator who forces the rear end of the counter portion of the shoe against the fixed back gage and then operates a treadle causing right and left pairs of front and rear crease plates to be moved into the rand crease of the shoe until depending abutments secured to the crease plates engage the counter portion of the shoe, the back gage and the crease plates constituting shoe positioning and supporting means.

The machine in many respects is similar to the machine disclosed in United States Letters Pat-

2

ent No. 1,307,285, granted June 17, 1919, on an application filed in the names of Samuel J. Wentworth and Frederick H. Perry, the front and rear crease plates forming a U-shaped opening through which the central part of the heel-seat portion of the attached outsole of the shoe positioned upon the crease plates is forced progressively by a roll. The roll is moved together with and in advance of the tab forming knife, a straight cutting edge of said knife moving along flat upper faces of the crease plates to split by a skiving cut surplus material having a horse-shoe shape from the margin of the heel-seat portion of the outsole extending above the crease plates.

In order to vary the length and width of the heel seat tab formed by the illustrative machine, the length and width of the U-shaped opening formed by the crease plates may be varied. Variations in width of the U-shaped opening may be effected by causing right and left pairs of crease plates to be moved toward each other as above described until depending flanges thereof engage the shoe counter, the width of which 20 varies in accordance with the size of the shoe. Variations in the length of the U-shaped opening are effected by initially adjusting the front crease plates lengthwise of the shoe, together with carriers for the shoulder forming knives, 25 with relation to the rear crease plates until forward edges of the front crease plates, along which edges the cutting edges of the shoulder forming cutters move in making their shoulder forming cuts, are in alinement with the ends of 30 the heel breast line previously drawn across the outsole of the shoe. In making their shoulder forming cuts the knives, in accordance with another feature of the invention, move inward and downward against the outsole, cutting movement of the cutters being limited by the engagement of stops, which are adjustably secured to the knife carriers, with the upper faces of the 35 crease plates, thereby insuring against the cutters moving below the crease plates and damaging the shoe upper.

It is desirable that the cutting edge of the heel seat reducing cutter in making its trimming cut move forward to the forward edges of the front crease plates, which edges, as above stated, 40 are moved into alinement with the heel breast line drawn on the outsole. With the foregoing in view and in accordance with a further feature of the present invention, the heel seat reducing knife during its cutting stroke is moved forward 45 by power to the forward edges of the front crease

plates irrespective of the lengthwise setting of said plates. Such action is effected by setting a cam in different positions in accordance with the lengthwise setting of the front crease plates and the shoulder forming cutters, the arrangement being such that a driving connection between power-driven means and the heel-seat reducing knife is rendered inoperative by mechanism actuated by the cam when the cutting edge of said knife reaches the forward edges of said crease plates. As said power-driven means is retracted it again becomes operatively connected to the knife and moves the knife back to its retracted or starting position. After the heel-seat portion of the outsole has been reduced and the roll and the heel seat reducing knife have been moved part way back to their retracted positions, the shoulder forming cutters are operated as above explained to form the heel breast receiving shoulders.

The various features of the invention will be understood and appreciated from the following detailed description read in connection with the accompanying drawings, in which

Figs. 1, 2 and 3 are side, front and plan views, respectively, partly broken away and partly in section, of the illustrative machine;

Fig. 4 is an enlarged side view, partly in section, of a portion of the machine;

Fig. 5 is an enlarged view, partly broken away, of a portion of the machine, cutters of which are in the process of forming heel breast receiving shoulders upon the attached outsole of a shoe presented to the machine;

Fig. 5^a is a section on line V^a—V^a of Fig. 5, illustrating shoe engaging abutments forming parts of the crease plates of the illustrative machine;

Fig. 6 is a vertical section, partly broken away, on line VI—VI of Fig. 3, illustrating mechanism through which a heel seat reducing knife of the machine is operated;

Fig. 7 is an exploded view showing in perspective the mechanism illustrated in Fig. 6;

Figs. 8 and 9 are sections on lines VIII—VIII and IX—IX of Fig. 1;

Fig. 10 shows the rear end of a shoe, the heel-seat portion of the attached outsole of which is about to be fitted by the use of the illustrative machine; and

Fig. 11 shows the shoe of Fig. 10 after the heel-seat portion of its outsole has been operated upon by the illustrative machine for the reception of a Louis heel, which is shown in phantom lines positioned on the heel seat of the shoe.

The illustrative machine is described with reference to reducing the heel-seat portion 20 (Figs. 3 and 10) of an attached outsole 22 of a shoe 24 for the reception of a Louis heel 26 (Fig. 11), and comprises right and left pairs of front and rear crease plates 28, 30 (Figs. 1, 3, 4 and 5) movable toward each other into the grand crease of the shoe, a fixed back gage 32 (Figs. 2, 3, 4 and 5) engaged by the rear end of the counter portion

of the shoe and co-operating with the crease plates in positioning the shoe in the machine, a bulger or roll 34 movable forward from a retracted position shown in Figs. 1, 2, 3 and 4, over the heel-seat portion 20 of the outsole of the positioned shoe; and constructed and arranged progressively to depress the central part of said heel-seat portion through a U-shaped opening 36 (Fig. 5) formed by the crease plates and a cutter or knife 38 (Figs. 1, 2, 4 and 5) which is movable forward, together with the roll, with its straight cutting edge 40 (Fig. 5) in engagement with flat

upper surfaces of the crease plates to split by a skiving cut a horseshoe-shaped piece of surplus material from the heel-seat portion of the outsole, thereby forming a heel seat tab 42 (Fig. 11) on the outsole.

During retractive movement of the knife 38 and the bulger 34 back to their rear starting positions, a pair of shoulder forming cutters or knives 44 are swung inward and downward from opposite sides of the outsole 22 past forward edges 46 (Figs. 3 and 5) of the front crease plates 28 to form heel breast receiving shoulders 48 (Fig. 11) upon the outsole and to sever from the outsole the horseshoe-shaped chip split from the outsole by the knife 38.

The operative parts of the machine are mounted upon a fixed upstanding frame 50, hereinafter referred to as the main frame. The rear crease plates 30 are secured by screws 52 (Figs. 1, 3, 4 and 5) to slides 54 which are movable at right angles to a vertical longitudinal plane 56 (Figs. 2, 3 and 5) of the machine along guideways 58 formed in brackets 60 secured to and forming part of the main frame 50. Formed at the bottoms of the slides 54 are racks 62 (Fig. 4) which are operatively connected to pinions 64 fitting in slots 66 (Figs. 1 and 4) of the brackets 60 and rotatably mounted upon horizontal shafts 68 which extend through bores 70 (Fig. 4), 71 (Figs. 1 and 3) of the brackets 60 and the main frame bosses 73, respectively, and are movable forward and rearward to a limited extent in said bores, for purposes which will be explained later. Meshing with the pinions 64 are a pair of gear segments 72 (Figs. 1, 2 and 4) which are keyed to horizontal shafts 74 rotatably mounted in bearings 76 (Figs. 1, 3 and 4), 78 (Fig. 1), respectively, of the bracket 60 and the main frame 50 and having secured to them pinions 80 (Figs. 1 and 3) operatively connected to racks 82 (Figs. 1, 2 and 3) secured by screws 84 to the upper ends of a yoke 86 secured to a slide 88 vertically reciprocable in a vertical guideway 90 of the main frame 50.

Pivotedly connected by a pin 92 (Figs. 1, 2 and 3) to a depending portion of the yoke 86 is a rod 94 arranged in telescopic relation with a hollow rod 96 (Figs. 1 and 2) the lower end of which is operatively connected by a fulcrum pin 98 to the rear end of a treadle 100. The rod 96 is provided with a flange 102 and the rod 94 has secured to it a collar 104 and surrounding said rods and interposed between said flange and collar is a strong coil spring 106 through which upward pressure is applied to the rod 94 upon actuation of the treadle 100 in a counterclockwise direction as viewed in Fig. 1. The treadle 100 is pivotally mounted upon a fulcrum pin 108 and is normally held against an adjustable stop 110 by a spring 112 the lower end of which is fixed to a stud 114 secured to the main frame 50 and the upper end of which is secured to a stud 116 carried by the yoke 86.

Each of the front crease plates 28 is slidably mounted for transverse movement in a guideway 118 (Figs. 3, 4 and 5) of a block 120 (Figs. 1, 2 and 4) having a depending boss into which is threaded a stud 122 (Fig. 4) fitting in a circumferential slot 124 formed in the corresponding shaft 68. The blocks 120 are supported against rotation upon the shafts 68, respectively, by pins 126 (Figs. 3, 4 and 5) which are secured to the brackets 60 and fit slidably in recesses 128 (Figs. 4 and 5) of the blocks 120 and also by pins 130 (Figs. 3 and 5) which are secured to the rear crease plates 30 and

fit slidingly in recesses 132 (Fig. 5) of the forward crease plates 28. With the above construction it will be apparent that the front crease plates 28 are moved transversely together with and to the same extent as their associated rear crease plates 30 and, through mechanism which will be herein-after described, may be moved forward and rearward, that is, longitudinally of the machine, with relation to their associated rear crease plates. The front and rear crease plates 28, 30 together form a multipart platen and may be referred to as such.

A forward portion 134 (Figs. 1, 2 and 8) of the treadle 100 is hinged for lateral movement with relation to the rear portion of the treadle and has secured to it a tooth 136 (Figs. 1 and 2) which may be moved by the operator into registration with any one of a plurality of teeth 138 of a treadle retaining plate 140 to hold the treadle depressed when the front and rear crease plates 28, 30 have reached their inward limits of movement into the rand crease of the shoe, said limits of movement being determined by the engagement of depending abutments 142 (Fig. 3), 144 (Figs. 3 and 5a) adjustably secured to the front and rear crease plates 28, 30, respectively, with the counter portion of the shoe.

In positioning work in the machine, the operator forces the rear counter portion of the shoe 24 arranged bottom up against the back gage 32 while holding the heel seat portion of the shoe horizontal and steps upon the treadle 100, causing the front and rear crease plates 28, 30 to enter the rand crease of the shoe, inward movement of the crease plates stopping when the abutments 142, 144 of the front and rear crease plates engage the counter portion of the shoe. Further downward movement of the treadle 100 causes compression of the spring 106, the operator then swinging the forward portion 134 of the treadle to the left, as viewed in Fig. 2, to cause the tooth 136 of the forward portion of the treadle to be moved into latching registration with one of the teeth 138 of the plate 140, thus retaining said treadle in its lowered position.

The lower portion of the back gage 32 fits in a slot 146 (Figs. 3 and 4) of the main frame 50 and is clamped in a fixed position in said slot by a setscrew 148 (Figs. 2, 3 and 4) threaded into the back gage and passing through an elongated slot 150 in the main frame.

It will be noted that the heel seat tab 42, the forward end of which is defined by the heel breast receiving shoulders 48, has approximately the same outline as the U-shaped opening 36 (Fig. 5) which is formed by the crease plates 28, 30 and through which the central part of the heel-seat portion 29 of the outsole is forced by the bulger or roll 34. The widthwise spacing of the right and left pairs of front and rear crease plates 28, 30 from each other varies in accordance with the width of the shoe into the rand crease of which the crease plates are forced. The lengthwise dimension of the heel seat tab 42 varies in accordance with the length of the cup of the heel to be attached to the shoe, the lengthwise dimension of the tab being approximately equal to the lengthwise dimension of the U-shaped opening 36, to the forward end of which opening the heel seat reducing knife 38 is moved by mechanism herein-after described.

The distance between the fixed gage 32 and the rear end of the U-shaped opening is constant for shoes of different sizes, the length of the U-shaped opening and accordingly the length of the heel-

seat portion of the shoe being varied as above stated by moving the front crease plates 28 forward or rearward with relation to the rear crease plates 30, mechanism which will be hereinafter described being provided for this purpose.

In order to vary the lengthwise positions where the shoulder forming cutters 44 operate upon the outsole 22 of the shoe 24 in accordance with the desired lengthwise positions of the heel breast 10 receiving shoulders 48, carriers 152 (Figs. 1 to 5), to which the cutters 44 are secured, are initially adjusted lengthwise of the U-shaped opening 36 to the same extent as the front crease plates 28, the arrangement being such that the cutters 44 in making their shoulder forming cuts move past the forward edges 46 (Figs. 3 and 5) of the front crease plates and form shear couples therewith.

The shoulder forming cutters 44 are secured in channels 156 (Figs. 2, 3, 4 and 5) of the carriers 152 by clamp screws 158 which are threaded into the cutters and pass through slots 160 (Figs. 4 and 5) in the carriers, the heads of the screws 158 being forced against the carriers to retain the cutters in their proper adjusted positions. Each 25 of the carriers 152 is mounted for free rotation upon its associated horizontal shaft 68 and is secured to the rear end of a spring 162 (Figs. 1, 3, 4 and 5) which surrounds said shaft and has its forward end secured to a collar 164 fixed to the shaft. Also secured to the horizontal shaft 68 30 are gears 166 (Figs. 1 and 3) meshing with gear segments 168 keyed to sleeves 170 (Fig. 1) which are rotatably mounted upon the lower horizontal shafts 74.

35 In meshing engagement with teeth 172 (Figs. 1 and 3) of the sleeves 170 are racks 174 the lower ends of which are secured to a yoke 176 screwed to a slide 178 (Figs. 1, 2 and 3) vertically movable in a guideway 180 (Fig. 1) of the main frame 50 and carrying a roll 182 (Figs. 1, 2 and 9) fitting in a cam groove 184 (Figs. 1 and 9) of a cam 186 secured to a drive shaft 188. The shaft 188 is operatively connected to a drive pulley 190 (Figs. 1, 2 and 3) by a one-revolution clutch 192 which 40 is actuated by a rod 194 connected at its lower end to the rear end of a treadle 196 fulcrumed upon a rod 197 (Fig. 1) secured to the main frame.

In order to move the front crease plates together with their associated knife carriers 152 into different forward and rearward positions in accordance with the desired length of the heel-seat portion of the outsole, there is provided a hand screw 198 (Figs. 1, 2, 3 and 4) which is threaded into the main frame 50 and has mounted on it an upstanding yoke 200 which straddles the right shaft 68 and fits in a circular groove 202 formed between the right collar 164 and a disk 204 secured by a screw 206 to the forward end of said shaft.

55 In order to move the left shaft 68 lengthwise in response to movement of the right shaft 68, said shafts are provided with circumferential axially spaced teeth 208 (Figs. 1, 3, 4 and 5) which 60 mesh with teeth 210 formed at the opposite ends of a shaft 212 rotatably mounted in bores 214 (Fig. 3) of the main frame 50, said shaft being restrained against movement lengthwise in said bores by collars 215 secured to said shaft.

70 It will be apparent that when the screw 198 is rotated it moves lengthwise with it the horizontal shafts 68 which, in turn, move, through the action of the blocks 120, the collar 164 and the spring 162, the cutter carriers 152 into different forward and rearward adjusted positions. In order to

effect the proper adjustment of the front crease plates 28 and the shoulder forming cutters 44, it is customary, before positioning the shoe in the machine, to place the heel 26 to be attached to the shoe upon the heel-seat portion of the attached outsole 22 of the shoe and to draw a line 216 (Fig. 10) across said attached outsole coincident with its heel breast line. The shoe is then positioned lengthwise and widthwise in the machine, as above described, by the back gage 32 and the crease plates 28, 30, the screw 198 being rotated until the forward edges 46 of the front crease plates 28 are in alinement with the heel breast line 216 marked on the outsole. With the heel-seat portion 20 of the attached outsole 22 of the shoe thus supported by the crease plates 28, 30, the shoulder forming cutters 44, when later moved along the forward edges 46 of the front crease plates 28, will form the heel breast receiving shoulders 48 which will coincide with opposite end portions of the heel breast line 216 on the outsole.

The carriers 152 for the shoulder forming cutters 44 are provided with rearwardly extending lugs into which are threaded stop screws 218 constructed and arranged to limit, by engagement with the flat upper surfaces of the front crease plates 28, the cutting movement of the cutters, the adjustment of said stop screws being such that the cutting edges 220 (Fig. 2) of the cutters do not move below the front crease plates 28, thus insuring against cutting the shoe upper.

The bulger or roll 34 is freely rotatable in bores of levers 222 (Figs. 1 to 6) which are mounted on a fulcrum pin 224 (Figs. 3 and 4) secured to an upstanding boss of a slide 226 to which the heel seat reducing cutter 38 is secured by screws 228 (Figs. 1 and 4). The slide 226 is movable, through mechanism hereinafter described, along a rectilinear guideway 230 (Figs. 3, 4 and 6) formed in the upper part of a casting 232 (Figs. 2, 3, 4 and 6) mounted upon the shaft 212 and on a shaft 234, said casting being held against movement lengthwise of the shaft 212 by collars 236 (Figs. 3 and 4) secured to the shaft 212 and being held against movement lengthwise of the shaft 234 by a pinion 238 (Figs. 3 and 4) and an arm 239 (Figs. 3, 5 and 7) which, as will appear later, are secured to the shaft 234. The rear ends of the levers 222 are operatively connected by a fulcrum pin 240 (Figs. 1, 3 and 4) to a link 242 mounted upon a pin 244 carried by a block 246 which is mounted for sliding movement on the slide 226 and into which is threaded a rod 250 slidably supported in a bore 252 (Figs. 1 and 3) of an upstanding boss of the slide. The levers 222 together with the link 242 form a toggle which, when the roll 34 and the knife 38 are in their retracted positions shown in Figs. 1 and 3, is almost straight by reason of the fact that the rear ends of the levers engage a sloping face 254 (Figs. 2 and 4) of a cam plate 256 of the main frame, a spring 258 (Figs. 1, 3 and 4) surrounding the rod 250 and positioned between the block 246 and the upstanding boss of the slide 226 then being compressed and a head at the rear end of said rod being spaced from said boss.

As the knife 38 together with the slide 226 is moved forward through mechanism hereinafter described to split material from the heel-seat portion 20 of the attached outsole 22 of the shoe 24, the levers 222, when permitted by the cam plate 256, rotate counterclockwise as viewed in Fig. 4 about the fulcrum pin 224 under the action of the spring 258, causing the roll 34 to force the

central part of the heel-seat portion 20 of the outsole through the U-shaped opening 36, the straight cutting edge 40 of the knife 38 which is in engagement with flat upper faces of the crease plates 28, 30 serving to split by a skiving cut a U-shaped chip of surplus material from the heel-seat portion of the outsole. The construction and arrangement of the toggle and the cam plate 256 is such that the toggle is broken to permit the roll 34 to be forced against the outsole just before the roll reaches the rear end of the U-shaped opening 36. During the retractive movement of the slide 226 the toggle, acted on by the cam plate 256, again starts to close as the roll moves rearward of the U-shaped opening 36.

In reducing the heel-seat portion 20 of the attached outsole 22 of the shoe, the cutter 38 moves forward to the corners 260 (Fig. 3) of the front crease plates 28 irrespective of the longitudinal setting of said plates, the extent of forward movement of the cutter being controlled by mechanism which will now be described and comprises a knock-off or disconnecting device 262 (Figs. 6 and 7) which regulates the amount of forward movement of the cutter in accordance with the longitudinal setting of the front crease plates.

The heel seat reducing cutter 38, as above stated, is secured by screws 228 to the cutter slide 226 which is movable in guideways 230 (Figs. 3, 4 and 6) of the casting 232 and has a rack 264 (Figs. 1, 4, 6 and 7) operatively connected to a gear segment 266. The gear segment 266 is loosely mounted between parts of the casting 232 upon the shaft 234 which is mounted for rotation in bosses 268 of the main frame. Formed integral with the gear segment 266 is a depending drive arm 270. Mounted upon a fulcrum pin 272 (Figs. 1, 3 and 7) secured to the main frame 50 is a gear segment 274 having a rearwardly projecting arm 276 which is universally connected to the upper end of a rod 278. Secured by a setscrew 280 to the shaft 234 and in meshing engagement with the gear segment 274 is the above-mentioned pinion 238 which, during each cycle of operation of the machine, rotates the shaft 234 through a fixed arc in response to movement of the rod 278.

There is also secured to the shaft 234 by a setscrew 284 the above-mentioned arm 239 in a horizontal bore 288 (Fig. 7) in the lower end of which slides a coupling pin 290 which is constantly urged to the left as viewed in Figs. 6 and 7 by a spring 292 and a tapered end 294 (Fig. 7) of which normally fits in a notch 296 formed in the depending arm 270 of the gear segment 266.

Freely rotatable upon the shaft 234 is a gear segment 298 operatively connected to a rack 300 forming part of a plate 302 secured by a screw 304 (Figs. 1, 3 and 6) to a block 306 having a bore 308 through which the right horizontal shaft 68 passes, the shaft having secured to it, in front of and behind the block, a pair of collars 310 (Figs. 1 and 3). With the above construction it will be apparent that when the shaft 68 is moved lengthwise upon rotation of the screw 198 the block 306, and accordingly the rack 300, will participate in such lengthwise movement, with the result that the gear segment 298 is rotated upon the shaft 234.

Formed integral with the gear segment 298 is a cam 312 (Figs. 6 and 7) which, during rotation of the shaft 234, is engaged by a pin 314 (Figs. 3, 6 and 7) slidable in a bore 316 (Fig. 7) of the arm 239. Secured to the pin 314 and extending through an elongated slot 318 in the arm 239 is a

stud 320 fitting between bifurcations of a lever 322 fulcrumed upon a screw 324 threaded into said arm 239. The lower end of the lever 322 is provided with a notch 326 in which fits a stud 328 passing through an elongated slot 330 formed in the arm and secured to the pin 290.

When the machine is at rest, the pin 290 engages the bottom of the notch 296 formed in the depending arm 270 of the gear segment 266, causing the arm upon its driving movement in a counterclockwise direction as viewed in Fig. 7 to drive the slide 226 and accordingly the heel seat reducing knife 38 forward. When the pin 314 during counterclockwise movement of the arm 239 engages the cam 312, it is displaced to the left as viewed in Fig. 7, causing the coupling pin 290 to be withdrawn from the notch 296 and accordingly breaking the driving connection between the arm 239 and the gear segment 266. The gear segment 298 and accordingly the cam 312 is set in a predetermined position in accordance with the setting of the front crease plates 28, the construction and arrangement being such that the driving connection between the arm 239 and the gear segment 266 is broken or rendered ineffective further to drive the knife 38 forward when the cutting edge 40 of the knife reaches the forward corners 260 (Fig. 3) of the front crease plates 28.

When the coupling pin 290 is withdrawn from the notch 296, it slides over a face 332 (Figs. 4 and 7) of the depending arm 270 and during retractive movement of said arm drops back into the notch 296 and upon continued retractive movement causes the heel seat reducing knife 38 to be moved back to its starting position.

The lower end of the rod 278 is operatively connected to the left end of a bell-crank lever 334 (Figs. 1 and 2) which is mounted upon a fulcrum pin 336 supported by the main frame 50 and carries a roll 338 fitting in a groove 340 of a cam 342 secured to the drive shaft 188.

In the operation of the machine briefly summarized, the operator, after drawing the heel breast line 216 (Fig. 10) across the attached outsole 22 of the shoe 24, presents the shoe, heel end first and heel-seat portion up, to the machine, the rear end of the shoe engaging the back gage 32 and the heel-seat portion of the shoe being held horizontal. The operator then depresses the treadle 100, causing the front and rear crease plates 28, 30 to move into the rand crease of the shoe 24 from opposite sides of the shoe until the abutments 142, 144 of the crease plates engage the shoe counter.

In case the forward edges 46 of the front crease plates 28 fail to line up accurately with the heel breast line 216 on the outsole 22 when these parts are viewed from above, pressure on the treadle 100 is relieved slightly and the screw 198 is rotated until the forward edges of the front crease plates are in proper alignment with said heel breast line. The treadle 100 is then again depressed, causing the abutments 142, 144 to be clamped against the shoe counter, further depression of the treadle causing the spring 106 to be compressed and accordingly a follow-up pressure to be exerted against the shoe counter by said abutments. The treadle 100 is then locked in its operative position by swinging the tooth 136 of the forward portion 134 of the treadle to the left as viewed in Fig. 2 into engagement with one of the teeth 138 of the retaining plate 140.

With the shoe thus positioned and clamped in

the machine, the treadle 196 is depressed, causing the one-revolution clutch 192 to be tripped, with the result that the roll 34 and the heel seat reducing knife 38 move forward to split the heel seat tab 42 (Fig. 11) from the outsole. When the roll 34 and the knife 38 have moved about half way back to their retracted positions, the shoulder forming knives 44 move inward and downward past the forward shear edges 46 of the front crease plates 28 to form the heel breast receiving shoulders 48 upon the outsole 22 and to sever from the outsole the horseshoe-shaped chip split from the outsole by the heel seat reducing knife 38. As above explained, the heel seat reducing knife 38 always moves to but not substantially beyond the forward inner corners 260 of the front crease plates 28 irrespective of the lengthwise setting of said plates. When the heel seat reducing and shoulder forming knives 38, 44 have moved back to their retracted positions and the machine has come to a stop, the operator releases the treadle 100, permitting the right and left pairs of front and rear crease plates 28, 30 to move away from each other back to their idle positions, shown in Fig. 3, and removes the shoe from the machine.

Although the invention has been described with reference to preparing the heel seats 20 of outsoles 22 of shoes 24 for the reception of Louis heels 26, it will be apparent that by replacing the front and rear crease plates 28, 30 as well as the shoulder forming and heel seat reducing knives 44, 38 with corresponding parts of slightly different shapes, the heel-seat portions of outsoles 35 may be prepared for the reception of Cuban heels.

Having described my invention, what I claim as new and desire to secure by Letters Patent of the United States is:

1. In a heel seat fitting machine, a fixed back gage, crease plates constructed and arranged to enter the rand crease of a shoe, means comprising cutters constructed and arranged to form heel breast receiving shoulders on the outsole 45 of the shoe and initially adjustable into different operative positions lengthwise of the shoe, a heel seat reducing knife mounted for trimming movement lengthwise of the shoe, and means for varying the amount of trimming movement of said knife in accordance with the setting of said shoulder forming means lengthwise of the shoe.

2. In a heel seat fitting machine, means comprising a back gage for positioning a shoe provided with an attached outsole having a heel breast line marked thereon, means co-operable with said back gage in measuring the heel seat of the shoe lengthwise, a heel seat reducing cutter movable lengthwise of the outsole, and means for varying the extent of movement of the cutter in accordance with the setting of said measuring means.

3. In a heel seat fitting machine, a multipart platen constructed and arranged to engage in a rand crease of a shoe, means for adjusting one or more parts of the platen relatively to the other parts, a power-operated cutter movable along said platen to reduce the heel-seat portion of an outsole of the shoe, and means for automatically varying the amount of movement of the cutter in accordance with changes in the adjustment of said one or more parts of the platen.

4. In a heel seat fitting machine, a plurality of crease plates which form a U-shaped opening and one or more of which are adjustable rel-

11

atively to the others to vary the shape of said opening, means for forcing the central part of the heel-seat portion of an attached outsole of a shoe through the U-shaped opening, a power-operated cutter movable lengthwise of said opening to reduce the heel-seat portion of the outsole, and means responsive to movement of said one or more crease plates for automatically varying the amount of movement of said cutter in accordance with changes in the adjustment of said one or more crease plates.

5. In a heel seat fitting machine, a fixed back gage for positioning a shoe lengthwise in the machine, means for supporting the heel-seat portion of an attached outsole of the shoe, a power-operated cutter which is movable forward along said outsole of the positioned shoe to reduce the heel-seat portion of said outsole, and means for automatically varying the length of the heel seat reducing stroke of the cutter in accordance with the desired length of the reduced heel seat to be formed on the outsole.

6. In a heel seat fitting machine, front and rear plates constructed and arranged to enter the rand crease of a shoe, a power-operated heel seat reducing cutter movable in a path along said plates, means for adjusting the front crease plates relatively to the rear crease plates lengthwise of said path, and means for automatically varying the extent of movement of the cutter along said path in accordance with the setting of said front crease plates.

7. In a heel seat fitting machine, right and left pairs of front and rear crease plates, a fixed back gage co-operating with the crease plates in positioning a shoe having an attached outsole, a heel seat reducing knife movable in a rectilinear path to reduce the heel-seat portion of the outsole of the shoe, means for adjusting the front pair of crease plates lengthwise of said path with relation to the rear pair of crease plates, and means responsive to adjustment of the front crease plates lengthwise of the path of movement of the knife for varying the extent of movement of the knife along said path.

8. In a heel seat fitting machine, means for positioning a shoe having an attached outsole, shear couples for forming heel breast receiving shoulders upon said outsole, power-operated means for reducing the heel-seat portion of the outsole of the shoe, mechanism for moving the shear couples into different adjusted positions lengthwise of the shoe in accordance with the desired positions at which the shear couples are to operate upon the outsole, and means responsive to movement of said mechanism for automatically varying the operation of the heel seat reducing means.

9. In a heel seat fitting machine, a pair of rear crease plates, a pair of front crease plates, said crease plates being constructed and arranged to form an opening, means for moving the rear crease plates toward and away from each other, dowel pin connections between each of the rear crease plates and its corresponding front crease plate for causing movement of the rear crease plates toward and away from each other to effect a like amount of movement of the front crease plates toward and away from each other, and means for moving the front crease plates into different adjusted positions toward and away from their associated rear crease plates.

10. In a heel seat fitting machine, a platen constructed and arranged to enter the rand crease of a shoe, cutters movable inward from

12

opposite sides of the shoe and toward the bottom of the shoe for forming heel breast receiving shoulders upon the outsole of the shoe, and stops movable together with the cutters and constructed and arranged to engage the platen to limit movement of the cutters toward the shoe.

5. In a heel seat fitting machine, means comprising crease plates for positioning a shoe having an attached outsole, knives movable inward from opposite sides of and toward the heel-seat portion of the shoe to form heel breast receiving shoulders upon the outsole of the shoe, means for yieldingly operating said knives, and stops movable with said knives and constructed and arranged to engage the crease plates to limit shoulder forming movement of the knives.

11. In a heel seat fitting machine, a platen constructed and arranged to enter the rand crease of a shoe, a pair of shafts, a pair of carriers loosely mounted upon the shafts, a pair of knives adjustably secured to the carriers, yieldable driving connections between the shafts and associated carriers, power-operated means for rotating said shafts to cause said knives to form heel breast receiving shoulders upon an attached outsole of the shoe, and stops movable together with the knives and the carriers and constructed and arranged to engage the platen to limit movement of the knives.

12. In a heel seat fitting machine, a pair of crease plates having forward shear edges, knives which are movable inward from opposite sides of a shoe positioned in the machine along said edges of the crease plates to form heel breast receiving shoulders upon an attached outsole of said shoe, and stops which are movable together with the knives and are constructed and arranged to engage the crease plates to limit shoulder forming movement of said knives.

13. In a heel seat fitting machine, a fixed back gage, a platen constructed and arranged to enter the rand crease of a shoe having an attached outsole and to co-operate with the back gage in positioning said shoe in the machine, said platen comprising a pair of crease plates having forward shear edges, knives which are movable inward from opposite sides of the shoe along said edges to form heel breast receiving shoulders on said outsole, means for moving the knives together

45 50 55 with the crease plates into different operative positions lengthwise of the positioned shoe to align the forward edges of the crease plates with a heel breast line marked on the outsole of the shoe, and stops which are movable together with the knives and are constructed and arranged to engage the crease plates to limit shoulder forming movement of the knives.

14. In a heel seat fitting machine, a fixed back gage, a platen constructed and arranged to enter the rand crease of a shoe having an attached outsole and to co-operate with the back gage in positioning said shoe in the machine, said platen comprising a pair of crease plates having forward shear edges, knives which are movable inward from opposite sides of the shoe along said edges to form heel breast receiving shoulders on said outsole, means for moving the knives together with the crease plates into different operative positions lengthwise of the positioned shoe to align the forward edges of the crease plates with a heel breast line marked on the outsole of the shoe, and stops which are movable together with the knives and are constructed and arranged to engage the crease plates to limit shoulder forming movement of the knives.

15. In a heel seat fitting machine, means comprising a fixed back gage for positioning a shoe having an attached outsole, shear couples for forming heel breast receiving shoulders upon said outsole, means for moving the shear couples into different adjusted positions lengthwise of the shoe to cause said couples to operate at the heel breast lines of outsoles of shoes of different sizes, a power-operated knife movable lengthwise of the shoe to reduce the heel-seat portion thereof, and mechanism movable in response to adjustment of the shear couples lengthwise of the shoe for causing the knife to move forward to the heel breast line of the outsole of the shoe being operated upon irrespective of the adjusted position of the shear couples lengthwise of the shoe.

16. In a heel seat fitting machine, a fixed back gage constructed and arranged to position length-

wise a shoe having an attached outsole, a platen comprising pairs of front and rear crease plates forming a U-shaped opening, means for moving associated pairs of front and rear crease plates toward each other to cause said plates to enter the rand crease of a shoe in order to position widthwise said shoe in engagement with said back gage, means for bodily moving the front crease plates into different adjusted positions lengthwise of the shoe to vary the length of said U-shaped opening and to align forward edges of the front crease plates with a heel breast line drawn across the outsole of the shoe, and power-operated means for reducing the heel-seat portion of the outsole and for forming heel breast receiving shoulders on said outsole to provide a heel seat tab.

17. In a heel seat fitting machine, opposite pairs of front and rear crease plates forming a U-shaped opening and constructed and arranged to enter the rand crease of a shoe, a fixed back gage for positioning the shoe lengthwise in the machine and for co-operating with said crease plates in positioning the shoe widthwise in said machine, a pair of shoulder forming knives movable along the forward edges of the front crease plates, said front crease plates being mounted for bodily adjustment lengthwise of said shoe to vary the length of the U-shaped opening, said knives being adjustable lengthwise of the shoe together with associated front crease plates to maintain the same relative relation of the knives with said plates irrespective of their lengthwise adjustment, and power-operated means for reducing the heel-seat portion of an outsole of the shoe and for co-operating with the shoulder forming knives to form a heel seat tab on said outsole.

18. In a heel seat fitting machine, a fixed back gage for positioning lengthwise a shoe having an attached outsole, front and rear crease plates constructed and arranged to enter the rand crease of the shoe, shoulder forming knives movable inward from opposite sides of said outsole, means for moving the front crease plates and associated knives into different adjusted positions lengthwise of the outsole in accordance with the position of a heel breast line on the outsole, a knife movable lengthwise of and forward along the outsole to reduce the heel-seat portion of the outsole, and means for moving the heel seat reducing knife different distances lengthwise of the outsole in accordance with the lengthwise setting of the front crease plates and the shoulder forming knives.

19. In a heel seat fitting machine, front and rear crease plates constructed and arranged to enter the rand crease of a shoe, a heel seat reducing knife which is provided with a cutting edge and is movable in a path extending along said plates, means for adjusting the front crease plates lengthwise of said path with relation to the rear crease plates, a cam movable into different positions in response to movement of the front crease plates into different positions lengthwise of said path, power-operated mechanism for moving the knife in one direction in said path to trim material from the heel-seat portion of an outsole of the shoe, and means actuated by said cam for rendering said mechanism ineffective to drive said knife further in said one direction when its cutting edge reaches a predetermined position with relation to the front crease plates.
20. In a heel seat fitting machine, means for positioning a shoe having an attached outsole, shear couples for forming heel breast receiving shoulders upon said outsole, means for moving the shear couples into different adjusted positions lengthwise of the shoe to cause said couples to operate at the heel breast lines of outsoles of shoes of different sizes, a knife movable in one direction lengthwise of the shoe to reduce the heel-seat portion thereof, a cam movable into different positions in response to movement of the shear couples into different adjusted positions lengthwise of the shoe, power-operated mechanism for driving the knife in said one direction, and means actuated by said cam for rendering said mechanism ineffective to drive said knife further in said one direction when a cutting edge of the knife reaches the heel breast line of the outsole.

JOHN T. LANCASTER.
